UNITED STATES PATENT OFFICE.

ANDREW W. GRAHAM, OF BUFFALO, NEW YORK, ASSIGNOR TO MEMORIALS ART COMPANY, INCORPORATED, OF BUFFALO, NEW YORK, A CORPORATION OF DELAWARE.

DESIGN FOR A SEPULCHRAL MEMORIAL.

49,339.

Specification for Design.

Patented July 11, 1916.

Application filed May 20, 1916. Serial No. 98,977. Term of patent 3½ years.

To all whom it may concern:

Be it known that I, ANDREW W. GRAHAM, a citizen of the United States, residing at Buffalo, in the county of Erie and State of New York, have invented a new, original, and ornamental Design for Sepulchral Memorials, of which the following is a specification, reference being had to the accompanying drawing, forming part thereof.

The figure is a perspective view of a sepulchral memorial, showing my new design.

I claim:

The ornamental design for a sepulchral memorial, as shown.

ANDREW W. GRAHAM.
